Primary Examiner — Wan Laymon**CLAIM**

The ornamental design for a slider handle for laparoscopic device, as shown and described.

DESCRIPTION

FIG. 1 is a perspective view of a slider handle for laparoscopic device in accordance with an embodiment of the present design;

FIG. 2 is an enlarged right side view of the slider handle for laparoscopic device of FIG. 1;

FIG. 3 is an enlarged left side view of the slider handle for laparoscopic device of FIG. 1;

FIG. 4 is an enlarged top view of the slider handle for laparoscopic device of FIG. 1;

FIG. 5 is an enlarged bottom view of the slider handle for laparoscopic device of FIG. 1;

FIG. 6 is an enlarged rear view of the slider handle for laparoscopic device of FIG. 1; and,

FIG. 7 is an enlarged front view of the slider handle for laparoscopic device of FIG. 1.

In FIGS. 1-7, the features of the slider handle for laparoscopic device shown in phantom lines are for illustrative purposes only and do not constitute a part of the claimed design.
